Letters Patent No. 105,142, dated July 5, 1870.

IMPROVEMENT IN THE APPLICATION OF CARBOLIC ACID FOR PREVENTING DECAY AND MILDEW IN SAIL-CLOTH, CANVAS, AND OTHER FIBROUS AND TEXTILE MATERIALS.

The Schedule referred to in these Letters Patent and making part of the same.

To all whom it may concern:

Be it known that I, WILLIAM A. TORREY, of Mont Clair, in the county of Essex and State of New Jersey, have invented a new and useful Improvement in Preventing Decay and Mildew in Sail-Cloth, Canvas, Tarpaulins, Awnings, Tents, Hammocks, and Coal-Bags, the same being also applicable to wall-paper, pasteboard, and to all textile and fibrous materials which are exposed to air and moisture; and I hereby declare the following to be a full and exact description of the same.

The beneficial effects of phenol or carbolic acid, and its related compounds, cresol, rosol, &c., in preventing decay in organic materials, have long been known, but have not been generally available, for the reason that these substances have only recently been produced in such purity, and in such quantities, and at such prices as to be used for this purpose.

Ever since the production of phenol as a regular manufacture or trade product, its use in preventing decay and mildew in textile fabrics and materials has been very imperfect, for the reason that no convenient process of applying it in a proper and in suitably regulated quantity was known.

Two modes of applying it have heretofore been used. The article to be preserved was either immersed in the carbolic acid, or in a mixture of carbolic acid and water. The first was too expensive and wasteful, besides proving injurious to goods which were to be subjected to an elevated temperature.

The mixture of the carbolic acid with water was not subject to this objection, but proved inefficient in practice, for the reason that carbolic acid is only very sparingly soluble in water, and the goods, after treatment in this watery mixture, generally contained spots not impregnated with the preservative agent, and, on exposure to air and moisture, were spoiled by decay and mildew, in the parts not protected. By my invention all these objections and difficulties are removed.

My invention consists in applying carbolic acid, so as to prevent decay and mildew in fibrous and textile fabrics, by means of its proper chemical solvents, such as the alcohols, the ethers, the hydrocarbons, the sulphide of carbon, and the like. These substances form, with carbolic acid, perfect solutions, of any degree of strength or concentration required, and the carbolic acid is in a condition to be carried to every part and fiber of the fabric treated with the solution.

In treating fabrics, such as the articles hereinabove mentioned, I find that a suitable proportion is about fifty parts of the solvent to one part of carbolic acid. Any fabric treated with this solution will be preserved against decay and mildew, in the most exposed situations.

I prefer to use, as the solvent, either the light hydrocarbons, such as benzene, gasoline, or naphtha, or

one of the alcohols, such as ordinary spirits, myrrhic alcohol, wood spirits, or amyl alcohol. But other solvents may be used, when found cheaper, or more readily obtained.

These solutions may be applied either by immersing the fabric in them, or by wetting or sprinkling the fabric with the solution.

The solutions may be mixed with paints, varnishes, starch, cements, paste, size, or other coating, to be applied to the fabric. These solutions of carbolic acid may be applied either after or during the process of manufacture, and the application may be repeated as often as found necessary.

I do not claim to have discovered the properties of carbolic acid as a disinfectant, and as a preventive of decay and mildew. Nor did I first discover the fact that it is soluble in the substances above mentioned; but

My invention consists in an improved mode of applying the well-known properties of carbolic acid, and its proper solvents, so as to effect a new and useful result, and in the preparation of compounds for this purpose; for, by my invention, the enormous loss from decay and mildew, in textile fabrics exposed to the air and moisture, is prevented.

For some purposes, combinations of two or more of the above solvents may be used. For the purpose of more ready application, the preserving liquid may be prepared by combining the acid with the proper quantity of solvent, and, in this, form, or combined with paints, varnishes, size, cements, and other coating compounds, constitutes new articles of manufacture, suitable for coating textile or fibrous materials, as above mentioned, and also for coating wood, stone, brick, and other materials, which are injured by mildew, and fungus vegetable growths, and decay, from exposure to air and moisture.

Having described my invention,

What I claim, and desire to secure by Letters Patent of the United States, is—

1. The process, herein described, for preventing decay and mildew in sail-cloth, awnings, and other textile and fibrous materials and manufactures, such as hereinabove mentioned, said process consisting in the combination of carbolic acid with the article to be preserved, by means of solvents, substantially as set forth.

2. The solutions herein described, for preventing decay and mildew in textile and other materials, prepared by combining carbolic acid with alcohol, ether, benzine, naphtha, or other solvent, as set forth.

3. The composition, formed by combining carbolic acid in solution with paints, oils, varnishes, and other coating compounds and materials, substantially as herein set forth.

WILLIAM A. TORREY.

Witnesses:

JUNIUS SCHENCK,
A. C. BENEDICT, Jr.
